CARD CABINET

Walter Buckeridge, Perth, Western Australia,
Australia

Application March 19, 1934, Serial No. 716,392

8 Claims. (Cl. 129—16.1)

This invention relates to improvements in card cabinets.

The improvements particularly concern card cabinets in which means are provided for dis-
closing the position of any required card by op-
erating a keyboard containing certain identify-
ing symbols associated with the card.

An important feature of the invention resides
in the association of the plurality of thin sep-
arating members, between which the cards are
placed and in the means whereby the thin sep-
arating members are moved up and down so as
to frictionally engage the cards although not
displacing the latter unless they have been other-
wise unlocked.

Associated with the foregoing are means for
unlocking the cards, such unlocking means being
associated with a keyboard. Means are also
provided for the purpose of partially ejecting a
selected card and for resetting the locking means
after a card has been replaced.

The foregoing and other features of the invention
will become apparent as the description
proceeds.

To enable the invention to be readily under-
stood, reference is now made to the accompany-
ing drawings, in which—

Fig. 1 is a front elevation of the card cabinet
in which, however, most of the details of con-
struction have been omitted from the left-hand
half.

Fig. 2 is a plan, sectional on the line A—A of
Fig. 1. In this view also, details of construction
on the left-hand side have been omitted.

Fig. 3 is an elevation of one side of the cab-
inet.

Fig. 4 is an elevation of the other side of the
cabinet. In this latter view the lower right-
hand portion has been cut away to avoid dupli-
cation as similar features are included in the
view shown in Fig. 3.

Fig. 5 is a side elevation in which the front
locking gate has been opened and, consequently,
shows the card partly ejected.

Fig. 6 is a part plan view showing details of
construction associated with the side shown in
Fig. 4, and

Fig. 7 is a similar view showing the resetting
mechanism in operation.

Fig. 8 is a sectional side elevation on the line
B—B of Fig. 2 when the locking gate is open.

Fig. 9 is a front elevation showing two adj-
acent sheet metal card separating members and
a card between them.

Fig. 10 is a sectional side elevation similar to

Fig. 8 except that it illustrates the position when
the cabinet is closed. In this view the keyboard
and locking gate have been omitted for clear-
ness.

Fig. 11 is a part elevation showing the guide · 5
rod and a view of some of the locking bars.

Fig. 12 is a part plan showing a view of some
of the keys, associated drag links, locking bars
and operating means therefor.

Fig. 13 is a plan showing a drag link, shrouded 10
crank member and vertical spindle operated
thereby.

Fig. 14 is a similar view except that the drag
link has come into operation, and

Fig. 15 is a plan of the view shown in Fig. 14. 15
Referring specifically to the drawings, there
is a base 20, supporting main side frame members
21 and 22. There are also intermediate frame
members 23 and 24 spaced relatively close to-
gether as shown in the drawings. There are fur-
ther intermediate members 25, 26, 27 and 28 that
form the cabinet into a plurality of compartments.

As illustrated in the drawings, there are six
compartments although in Fig. 1 there are only
two compartments that are shown containing the
sheet metal card separating members. There are
also distance members 29 and 30 supporting the
lower portions of the intermediate frame mem-
bers and connected to the main side frame mem-
bers and central intermediate members, and fur-
ther, there is a top frame member 31 which has
a longitudinal opening for most of its length, for
a purpose that will subsequently be apparent.

Bearing in the frame members 21, 22, 23 and 24
is what may be termed an elevating shaft 32. 25
At each end, immediately outside the frame mem-
bers 21 and 22, this shaft is provided with a cam,
one of which is referenced 33 and shown in dotted
lines in Figs. 3 and 5. These cams operate a mas-
sive elevating link 34 on each side. Each of these
elevating links is pivoted at 35 to an elevating
member 36. The elevating members 36 act as

bearings for longitudinally disposed shafts 37, 38
and 39, the said shafts being also connected to-
gether by an intermediate member 40 placed be-
tween the central frame members 23 and 24. At
each end the shafts 38 and 39 are connected with
a link 41 that serves as a guide for the elevating
link 34. The end of the elevating shaft 32 is con-
nected to a crank 42 in turn connected to an op-
erating handle 43. There are a plurality of thin

sheet metal card-separating members 44 placed
in each of the compartments of the cabinet. Each
of these card-separating members is perforated
so that the three shafts 37, 38 and 39 pass through

45

50

55

them. In consequence, the card-separating members 44 move with the shafts. Between these sheet metal separating members will be washers 45. Each card used is placed between a pair of the thin sheet metal members, the cards being referenced 46.

Associated with the card-separating members are space indicators 47. These comprise small link members, there being one between each pair 10 of separating members and the said indicators being slotted and capable of turning on a pin 48 that passes through the lower front portion of the sheet metal members 44 in each section of the cabinet. In the front of the cabinet there 15 is a keyboard, the keys indicating appropriate symbols, letters or numerals as circumstances require. A key, referenced 49, is attached to a bell crank lever 50, in turn pivoted to a drag link 51. The drag link is at the other end pivoted 20 to a shrouded crank 52 that gives a partial turn to a vertical spindle or rod 53 through a pin 54 attached thereto. By reason of the construction shown, after the spindle 53 has been given a partial turn to the extent indicated in Fig. 14, the shrouded crank 52 can move back to the position shown in Fig. 13 without dragging 25 the spindle 53 with it, the said spindle being independently reset as will be subsequently explained. Also connected to each vertical spindle 30 53 will be a crank 55 pivoted to a drag link 56 that is connected to an unlocking bar 57. For each key, therefore, there is a bell crank lever such as 50, a drag link such as 51, a crank 52, a lug 52', a vertical rod 53, a crank 55, drag link 35 56 and unlocking bar 57. Each of the unlocking bars 57 is at the ends provided with offset slots 58 that control the position of the locking bar as each slot works around a vertical guide rod 59. The effect of depressing a key is to pull the 40 drag link 51, turn the crank 52 through it moving lug 52' which abuts and moves pin 54, thereby turning the vertical rod 53, this will turn the crank 55 and exert a pull on the drag link 56 that is communicated to the locking bar 57. This locking bar 57 on being pulled has 45 its movement controlled by the slots 58 and guide rods 59 that cause the locking rod to be moved backwards, as is shown with the upper locking rod in Fig. 12.

50 At the front of the cabinet there is a locking gate comprising vertical hinged gate members 60 and 61 and horizontal gate members 62 and 63. At each side is pivoted a cam-faced latch 64 fashioned and adapted to lock on pins 65 connected to the side frame of the cabinet. Pivoted to the side gate member 61 is a slotted link 66 having a holding notch. This slotted link works on a guide pin 67 and it has pivoted thereto an intermediate link 68 that is in turn pivoted to the end of an operating lever 69. The said operating lever is connected to a rocking arm 70, the shaft of which passes longitudinally through the cabinet, there being a corresponding rocking arm on the other side of the machine. Each rocking arm 70 is provided with a slot by means of which it engages a pin 71 connected to an ejecting bar 72. On each side of the cabinet is a resiliently controlled rod 73 provided with a pin 74 that will permit full forward movement of the said rod so long as the pin is in line with upper or lower notches 75 in the lifting member 36. Each of the rods 73 is engaged by a spring 76 that tends to pull it forward, an action that is prohibited so long as the front locking gate is closed. On one side, being 75 the side illustrated in Fig. 4, there is a pres-

sure arm 77 connected to the rod 73 and such pressure arm is adapted to engage a notched arm or member 78 fixed to rod 79 that is inclined to the cabinet as viewed in plan. When the rod 73 is moved from the front to the back the pressure arm 77 engages and presses the notched arm 78 until the notch is reached, when the pressure arm slips through the notch and behind the arm 78. When the rod 73 is again allowed to move forward the pressure arm resets itself so as to engage the front of the notched arm 78.

On the same side of the cabinet there are vertical rods 79 and 80, the former being connected to the notched arm 78 while the latter is pivoted at the top and the bottom. Connecting these 15 rods together are horizontal rods 81. There is a spring 82 connected to the vertical rod 80 which tends to keep it and its associated parts in the position shown in Fig. 6.

The method of operating the cabinet is as follows:—

The cards used are each provided with a number of projections or serrations corresponding to the particular identifying characteristics of the card in question; thus if names are employed all 25 such parts of the card corresponding to letters not part of the name are cut away so that there remains a number of projecting lugs corresponding to the particular letters making up the name.

A card is pushed into the cabinet in an upward position as shown in Fig. 10 between any two of the thin sheet metal separating members 44 where a vacant space is indicated by the forward position of an indicator 47. After the card has been pushed into position the corresponding indicator 47 is pushed to the upright position showing that the space between the particular sheet metal separating members is occupied. The front locking gate is then moved down from the position shown in Fig. 5 to the position shown 30 in Fig. 10. The effect of doing this is that the ejecting bar 72 is retracted and any locking bars 57 that may be in the unlocked position are reset to the locked position by reason of the pressure exerted by the bar 79 against their ends. The 35 operating handle 43 is then turned to take up the position shown in Fig. 2 and this has the effect of raising the separating sheet metal members 44 although the position of the cards in the cabinet is not affected, being merely frictionally engaged by the said separating members.

When it is desired to remove a card, the keys containing the symbols characteristic of the card are depressed. This has the effect of retracting the corresponding locking bar members 57 so 55 that the particular card is now free to move downwardly. The handle 43 is now turned and this has the effect of lowering all of the thin sheet metal separating members 44. The effect of doing this is to frictionally engage all of the 60 cards that are locked but not to move them although the card that has been released is moved down to a lower position. In such lower position the bottom edge comes into or below alignment with the ejecting bar 72. In consequence, when 65 the front locking gate is released and moved to the position shown in Fig. 5, the lever 69 is turned and this has the effect of pushing the ejecting member forward. In doing this it pushes the card 46 forward to the position shown 70 in Fig. 8. The card, in being pushed forward, pushes the indicator 47 to a forward position. The required card is then removed. When it is replaced the corresponding indicator 47 is pushed back and the locking gate moved until it takes 75

the position shown in Fig. 3. In doing this the ejecting member 72 is retracted and the locking bars 57, which were retracted when certain characteristic keys were operated, are pushed so that 5 they take up a normal locking position. The operating handle is then turned back to the position shown in Fig. 2 and this raises all of the thin sheet metal separating members 44 to the level shown in Fig. 10. It will be obvious that when 10 the relevant locking bars 57 are retracted, thereby unlocking the serrations on the card, that the card is capable of moving downwards to an extent approximately equal to the distance between adjacent locking bars and this actually is about 15 the extent of downward movement of the thin sheet metal separating bars 44.

I claim:—

1. Improvements in a card cabinet comprising a plurality of thin separating members, cards 20 adapted to be frictionally retained between said separating members, means for individually locking at times said cards, and means for moving said separating members as a whole whereby any card not locked will also be moved.
  2. Improvements in a card cabinet comprising a plurality of thin separating members, cards 25 adapted to be frictionally retained between said separating members, means for individually locking at times said cards, means for moving said separating members as a whole whereby any card not locked will also be moved, and means for partially ejecting any unlocked card after it has been moved.
  3. Improvements in a card cabinet comprising 30 a plurality of thin separating members, cards adapted to be frictionally retained between said separating members, means for individually locking at times said cards, means for moving the separating members as a whole whereby any card not locked will also be moved, keyboard controlled means for actuating said card locking 35 means and for releasing the cards from said locking means and an ejecting bar that pushes a released and moved card forward.
  4. Improvements in a card cabinet comprising 40 the combination of a plurality of thin separating members, cards placed between said members and supported thereby, shafts passing through the said members thereby connecting them, means for raising and lowering the separating members and the shafts in unison, a plurality of locking bars adapted at times to engage serrations in the cards placed in the cabinet for locking the cards so engaged against movement 45 with said separating means, a keyboard having a plurality of keys, each key controlling the release of one locking bar, an ejecting bar that moves forward and partially ejects an unlocked and moved card and means for operating the said ejecting bar.
  5. Improvements in a card cabinet comprising 50 the combination of a plurality of thin separating members, cards placed and frictionally supported between said members, shafts passing through 55 the said members thereby connecting them, means for raising and lowering the separating members and the shafts in unison, a plurality of locking bars engaging serrations in the cards placed in the cabinet, a keyboard having a plurality of keys, each key controlling the release of one locking bar, an ejecting bar that moves forward and partially ejects an unlocked and moved card, means for operating the said ejecting bar and means for resetting the locking bars 60 after a released card has been replaced in the cabinet.
6. Improvements in a card cabinet comprising the combination of a plurality of thin separating members, cards placed between said members, 15 said cards being in frictional engagement with said members, shafts passing through the said members thereby connecting them, means for raising and lowering the separating members and the shafts in unison, a plurality of locking bars 20 engaging serrations in the cards placed in the cabinet, a keyboard having a plurality of keys, each key controlling the release of one locking bar, an ejecting bar that moves forward and partially ejects an unlocked and moved card, 25 a lever controlling the operation of the ejecting bar, means for resetting the locking bars after a released card has been replaced in the cabinet, a locking gate at the front of the cabinet and means connected to the locking gate for moving 30 the lever that controls the operation of the ejecting bar.
7. Improvements in a card cabinet comprising a plurality of thin separating members, cards 35 adapted to be frictionally retained between said separating members, means for individually locking at times said cards, means for moving the separating members as a whole whereby any card not locked will also be moved, keyboard control means for actuating said card locking 40 means and for releasing the cards from said locking means, an ejecting bar that pushes a released and moved card forward and a plurality of indicators in the form of links one placed between each pair of separating members.
8. Improvements in a card cabinet comprising 45 a plurality of thin separating members, cards adapted to be frictionally retained between said separating members, means for individually locking at times said cards, means for moving the separating members as a whole whereby any card not locked will also be moved, keyboard control 50 means for actuating said card locking means and for releasing the cards from said locking means, an ejecting bar that pushes a released and moved card forward, a plurality of indicators in the form of links, one placed between each pair of separating members, a resetting bar that presses against bars that have been unlocked, a notched 55 arm connected to the resetting bar, a pressure arm engaging the notched arm, a locking gate, and a rod operated by said locking gate and connected to the pressure arm.

WALTER BUCKERIDGE.
